UNITED STATES PATENT OFFICE.

CLAUDIUS M. PETTY, OF WILKESBORO, NORTH CAROLINA.

AEROPLANE.

Application filed January 12, 1923. Serial No. 612,269.

To all whom it may concern:

Be it known that I, CLAUDIUS M. PETTY, a citizen of the United States, residing at Wilkesboro, in the county of Wilkes and State of North Carolina, have invented certain new and useful Improvements in Aeroplanes; and I do hereby declare the following to be a full, clear, and exact description of the invention, such as will enable others skilled in the art to which it appertains to make and use the same.

This invention relates to aeroplane steering and driving mechanism.

It is aimed to provide a construction which is a complete aeroplane and generally improved over that in Letters Patent 1,360,976, issued to me on November 30, 1920, in that the present invention includes a steering gear of mechanism which is lacking in the patented structure.

Another object is to provide a novel steering and driving mechanism to be particularly used with the plane means of the said patent.

One more object is to provide a construction having upper and lower wings and otherwise different and improved over the patented structure.

It is further aimed to provide novel means whereby the possibilities of use of an aeroplane or the like in the matter of maneuvering may be increased due to its more flexible drive and steering control.

Specific objects and advantages will become apparent from a consideration of the description following taken in connection with accompanying drawings illustrating one practical embodiment.

In said drawings:—

Figure 1 is a plan view of an aeroplane or airship constructed in accordance with my invention, partly broken away;

Figure 2 is a side elevation thereof;

Figure 3 is a substantially central longitudinal sectional view thereof partly broken away and on an enlarged scale;

Figure 4 is a fragmentary horizontal sectional view through the machine taken substantially along the line 4—4 of Figure 2;

Figure 5 is a cross sectional view on the line 5—5 of Figure 3, and

Figure 6 is an enlarged detail sectional view on the line 6—6 of Figure 1.

In reducing the invention to practice, an aeroplane or heavier than air type of air

craft has been shown by way of example, it being understood that the same may be a monoplane, biplane or otherwise. The fuselage is shown at 10 mounted upon ground wheels 11 supported in hangers 12 depending from the fuselage. Upper and lower sustaining planes 13 and 14 are connected together and to the fuselage 10 by suitable struts or a frame work at 15. The fuselage is open at 16 to provide the cockpit and within the fuselage the operator's seat at 17 is provided. One or more stirrups 18 may be provided to assist the pilot in climbing into the fuselage and rubber or other mats or treads 13^a may be provided on plane 13 to enable the pilot to obtain a foothold thereon should it be necessary to climb thereon as for inspection or repair.

The machine is adapted to be propelled in any suitable manner for instance by means of an engine at 18, which may be of the usual type, speed and capacity. The drive shaft of said engine is designated 19 and extends forwardly therefrom and through the fore end of the fuselage and has the main propeller 20, by means of a hub 21, journaled on the shaft 19 and held in place thereon as by means of a nut 22. Auxiliary or lifting propellers are provided at 23, angularly disposed at opposite sides of the fuselage and having shafts 24 to which they are keyed, journaled in bearings 25 extending laterally of the fuselage. A gear casing 26 is located within the fuselage and the shafts 19 and 24 are journaled therein. On shaft 19 within casing 26 a gear wheel 27 is keyed which meshes with gear wheels 28 keyed on the shafts 24 and located within the gear casing 26. Slidable along the shaft 19 and keyed or splined thereto at 19^a so as to rotate therewith is a clutch head 29. The hub 21 is hollow and said head 29 and hub having coaxial and engageable inclined clutch faces at 30 so that the head may engage the hub and thus connect the propeller for driving or rigid relation with shaft 19. Clutch 29 may be operated by any suitable means as from a lever 31 pivoted to a link 32 in turn pivoted to a link or leaf 33 pivoted at 34 on the casing 26. A link 35 is pivoted to lever 31 and in any suitable manner connected with the head 29 as by means of a yoke at 36, to which link 35 is pivoted and which yoke is disposed in an annular groove 37 provided about the

90

95

100

105

110

head 29. Head 29 also is disposed in an opening 38 at the fore end of the fuselage to guide and reinforce the same and shaft 19.

As a result, it will be seen that operation 6 of the engine 18 will through the medium of the shaft 19, gear wheels 27 and 28 and shafts 24 impart movement to the lifting propellers 23. When desired, the lever 31 may be actuated so as to apply or release the 10 clutch head 29 by sliding movement, into and out of engagement at the surfaces 30 with the propeller 20 so as to drive or disengage it. It will be realized that lever 31 may be actuated in any suitable manner, that 15 is by hand if the size of the machine permits, or means may be connected to the lever 31 so that it may be actuated from a convenient location adjacent the seat 17. Due to the fact that the surfaces 30 are conical, a very 20 effective frictional connection is afforded between head 29 and propeller 20.

If desired means may be provided to slide gear 27 out of mesh with gears 28 so that propellers 23 may remain idle while propeller 20 alone operates.

The planes 13 are provided with ailerons at 39 and 40, respectively. Novel means are provided for controlling the position of the ailerons 39 and 40 and to this end a bearing 30 41, suitably fastened as at 42 within the fuselage 10 and adjacent to the seat 17. A rock shaft 43 is journaled in the bearing 41 and has an operating arm or lever 44 extending therefrom and pivoted thereto on a horizontal axis as at 45. The forward end of shaft 43 has extensions 45 thereon to which cables 46 are attached and which are also attached as at 47 to studs 48 depending from the ailerons 39. Said shaft 43 is held against 35 longitudinal displacement relative to the bearing 41 by means of nuts 49 screw threaded on the shaft and abutting opposite ends of bearings 41. Cables 46 are of any suitable flexible material and pass through the fuselage 10 plane 14 and over suitable guide pulleys at 50 located at various locations on the fuselage and plane 14. Rods 51 are pivoted at 52 to the plane 13 and 53 to the plane 14. Studs 54 rise from the ailerons 40 and a flexible cable 55 is connected to studs 54 at opposite ends, and passes for the most part interiorly of the plane 13 and is guided over pulleys 56 located thereon. Ailerons 39 and 40 are pivoted on horizontal axes by 45 means of hinges at 57 and 58 to the respective planes 13 and 14. As a result, arm 44 may be rocked to the right or left as desired which will rock the shaft 43 and thus draw the cables 46 and 55 and rods 57, imparting corresponding movement to the ailerons 39 and 40, on one side of the machine and opposite movement to the ailerons 39 and 40 on the other side of the machine, that is to say, when the ailerons on one side of 55 the machine raise, the ailerons on the other

side of the machine lower and vice versa. The lever 44 may be manipulated by hand or by pressure of the knee against the same or otherwise as preferred.

Laterally extending rear planes are provided at opposite sides of the fuselage 10 as at 59, being rigidly connected to the fuselage. Lifting planes 60 are movably connected to the planes 59 on horizontal axes by means of hinges at 61. Draw cords or cables 70 of any suitable flexible material at 62 are fastened to studs 63 on planes 60 and pass over guide pulleys 64 on the planes 59 and through guide openings 65 into the fuselage 10. A cable 62 is thus connected both below 75 and above and to each of the planes 60 as best shown in Figure 3. The inner ends of cables 62 are attached in any suitable manner to a control element or frame at 63 as to studs 64 thereof extending from a shaft 65 journaled on a horizontal axis by means of trunnions 66 in bearings 67 fastened within the fuselage. (See Figure 5.) It will thus be seen that the uppermost cables 62 are fastened above the axis of shaft 65 and the lowermost cables 62 are fastened below the axis of the shaft 65.

In order that the planes 60 may be operated in unison and proportional to the operation of the ailerons 39 and 40, a connection is made between the arm 44 and control elements 63 which may be a rod 68 passing through said lever and to the elements 63 as at 69.

Thus when the arm 44 is rocked in either direction, corresponding movement will be imparted through the cable 68 to the elements 63, tilting or rocking the latter from its fulcrum at 66 and drawing upon the cables 62 so as to correspondingly tilt or 1 actuate the planes 60.

The rudder is shown at 70 hinged on a substantially vertical axis as at 71 to a pin or bade 72 rigid with and rising vertically from the fuselage 10. Rudder 70 may be 1 actuated or swung in any approved manner, and to this end may have studs 73 extending laterally from opposite sides thereof and to which flexible cables 74 are fastened which pass through openings 75 in the fuselage 10 and are connected to the lever 75 pivoted at 76 to the bearing 41. Lever 75 may be operated by the feet and to this end have pedals at 77 preferably upturned at their forward ends at 78 to facilitate better engagement with the shoes of the operator.

It will thus be seen that by actuating the lever 75 through the medium of the foot or otherwise, that a drawing strain will be exerted on the cable 74 which will correspondingly turn the rudders 70 to steer the machine.

As merely a preferred embodiment has been illustrated and described, it is to be

understood that changes in the details may be resorted to provided they fall within the spirit and scope of the invention.

I claim as my invention:—

- 5 An airship having a fuselage, a plane carried thereby, an aileron associated with said plane, a substantially tubular bearing arranged longitudinally within the fuselage and at an inclination, said bearing being open intermediate its ends, a rock shaft journaled in said bearing against movement longitudinally of the bearing, means to actuate said aileron through rocking movement of said shaft, an auxiliary plane, a
- 10

control element for said plane movable on 15 an axis at substantially a right angle to the rock shaft, a lever by means of which said shaft is rocked extending therefrom through the opening of the bearing, means connecting said lever to said shaft for movement independently thereof on an axis substantially parallel to the axis of the control means, and a rod connection between said lever and control means.

In testimony whereof I affix my signature.

CLAUDIUS M. PETTY.
